(57) **CLAIM**

The ornamental design for a terminal metal fitting, as shown and described.

DESCRIPTION

FIG. 1 is a front, top, and right side perspective view of a terminal metal fitting showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a cross-sectional view thereof, taken along line 8-8 of FIG. 4; and,

FIG. 9 is a partially enlarged cross-sectional view thereof, showing a portion defined by lines B-B and lines C-C in FIG. 8.

The broken lines shown in the drawings are included for the purpose of illustrating unclaimed environment only, and form no part of the claimed design. The dot-dash broken lines shown in the drawings represent an unclaimed boundary line, and form no part of the claimed design.
